COASTER FOR DRINKING GLASSES AND THE LIKE

Donald M. Davis, Fort Payne, Ala., assignor to Hi-Jac Corporation, Fort Payne, Ala., a corporation of Alabama

Application January 24, 1956, Serial No. 560,958

9 Claims. (Cl. 215—100.5)

The present invention relates to coasters for drinking vessels such as drinking glasses. Coasters for drinking glasses have frequently been used in the past for the primary purpose of preventing moisture or condensation forming on the exterior of the glasses from damaging surfaces on which the glasses rest and to prevent such moisture or condensation from dripping while the glasses are being used. The present invention relates to improvements in coasters for this purpose.

The coaster of the present invention consists essentially of a ring-like body member, which is open at least at its upper end to receive the bottom of a drinking glass, and a tubular fabric sleeve member of moisture absorbent textile material. The sleeve member at least partially covers the lower end of the body member, completely covers the outer surface of the body member, and extends downwardly into the interior of the body member to form a fabric liner for the interior surface of the body member. The tubular sleeve member is removable from the body member for washing or cleaning.

One of the primary objects of the present invention is to provide a coaster for a drinking glass and the like which can easily be applied to the glass after the glass has been filled and which provides a relatively wide and tip-proof base of decorative character which is securely held by the glass.

Another object of the invention is to provide a coaster for a drinking glass or the like which substantially eliminates any possibility of condensation running or dripping from the exterior of the glass on to a supporting surface or on to the clothing of a user of the glass.

Another object of the invention is to provide a coaster having the foregoing objects and advantages which does not conceal the decoration appearing on the side of a drinking glass.

Still another object of the invention is to provide a coaster which will fit a wide variety of sizes of drinking glasses or similar vessels.

Another object of the invention is to provide a coaster having a more or less rigid body member and a decorative and moisture-absorbent sleeve-like cover and lining which can be removed from the body member for washing or cleaning.

The foregoing and other objects and advantages of the invention can be better understood by reference to the following description and the accompanying drawing wherein:

Figure 1 is a view partly in side elevation and partly in section of a tubular fabric sleeve member forming a part of the coaster;

Figure 2 is a vertical sectional view of the assembled coaster having a drinking glass positioned therein;

Figure 3 is a view similar to Figure 2 but illustrating a modified form of the invention;

Figure 4 is a fragmentary sectional view of a further modified form of body member for the coaster; and

Figure 5 is a perspective view of still a further modified form of body member for the coaster.

2

A tubular fabric sleeve member is designated generally by the reference numeral 5. This sleeve member is preferably, although not necessarily, of knit fabric and is open at both its upper and lower ends. The upper and lower ends of the sleeve member 5 are preferably of lesser normal diameter than the intermediate portion thereof. This constricting of the ends of the sleeve member may be accomplished by incorporating therein yarns or strands of resiliently stretchable material, such as rubber. A plurality of stretchable yarns are indicated by the reference numeral 6 as surrounding and constricting the open lower end portion 7 of the sleeve member. A plurality of stretchable yarns 8 are incorporated in and constrict the open upper end 9 of the sleeve member. An intermediate portion 10 of the sleeve member 5 and the lower portion 11 thereof are illustrated as being formed of terry knit fabric. The upper portion 12 of the sleeve member 5 is illustrated as formed of plain knit fabric.

A ring-like body member is illustrated in Figure 2 and is designated by the reference numeral 13. The body member 13 may be formed of any more or less rigid material such as plastic and as illustrated in Figure 2 is of inverted frusto-conical shape. The body member 13 is illustrated as being open at its upper and lower ends.

The body member 13 may be inserted through the upper end 9 of the sleeve member 5 by stretching the yarns 8. The upper end portions 12 of the sleeve member may then be positioned in the interior of the body member as illustrated in Figure 2. A drinking glass 14 or other similar vessel may then have its bottom inserted into the larger upper end of the body member 13. The upper portion 12 of the sleeve member forms an absorbent textile liner between the exterior of the glass 14 and the interior surface of the body member 13. The constricted upper end 9 of the sleeve member remains more or less constricted during use of the coaster and, as seen in Figure 2, underlies a portion of the bottom of the glass 14. The lower end 7 of the sleeve member also remains at least partially constricted during use of the coaster. The bottom portion 11 of the sleeve member forms a cushion for the lower edge of the body member 13 and also provides an absorbent base to prevent moisture from collecting on a surface on which the coaster may rest.

The glass 14 will normally be securely wedged within the coaster because of the taper of the body member 13 and the taper of the glass 14. However, it is not essential that the body member 13 and the glass 14 have similar tapers because of the fact that the resiliently constricted end 9 of the fabric sleeve 5 acts to cushion the glass 14 against entering too far into the body member 13. When it is desired to use the coaster illustrated in Figure 2 with glasses having a smaller base, the body member 13 may be inverted within the sleeve member 5 and the coaster will function in a satisfactory manner.

The terry knit portions 10 and 11 of the sleeve member 5 are preferably of such extent that they constitute the only exposed portions of the sleeve member when the coaster is in use. In other words, the plain knit portion 12 of the sleeve member 5 is preferably the portion of the sleeve member which forms the liner between the glass 14 and the body member 13.

The coaster covers only the lower portion of the glass 14. Hence any decoration on the glass will remain visible.

The sleeve member 5 may easily be removed from the body member 13 to permit washing or cleaning of the sleeve member.

The coaster illustrated in Figure 3 differs from that illustrated in Figure 2 only in the nature of the body member. The sleeve member and the glass are identical to those described above and for that reason the same

reference numerals are used thereon. The body member 15 illustrated in Figure 3 is constructed of resiliently stretchable material such as rubber and is preferably normally cylindrical. The sleeve member 5 is positioned on the body member 15 in the manner described above. When the bottom of the glass 14 is inserted in the coaster the upper portion of the body member 15 will be stretched and deformed as indicated in Figure 3. This form of the coaster can thus be used with glasses 14 having bottoms of a variety of diameters.

Figure 4 illustrated a modified form of body member which is designated generally by the reference numeral 16. The body member 16 consists of a laminated core 17 of material such as paper which may be wound to form the body member of inverted frusto-conical shape. All surfaces of laminated core 17 are covered by any suitable moisture resistant coating 18. The body member 16 may be used in the same manner as the body member 13 illustrated in Figure 2.

Figure 5 illustrates a further modified form of body member which is designated generally by the reference numeral 19. The body member 19 is in the form of a ring which is split as indicated at 20. The split ring may be either cylindrical or frusto-conical and may be formed of material such as plastic, metal, rubber or any other material which is capable of returning to the original configuration after the split ring has been slightly expanded. The body member 19 may be inserted in the sleeve member in the same manner as the body members described above. Insertion of the base of a glass into the assembled sleeve and body members will cause the body member 19 to expand slightly and to firmly grip the glass.

The body members 13, 15, 16 and 19 are not visible during use of the coaster. Consequently, those body members may have printed matter, such as instructions, trademarks, or advertising material thereon.

It will be seen from the foregoing description that I have provided coasters having the advantages enumerated above. The assembled coasters themselves are decorative and do not conceal decorations on the glasses. The coasters are held securely on the glasses and provide stable bases for the glasses. Moisture condensing on the glasses must saturate the portion 12 of the fabric sleeve member before moisture can accumulate in the portion 11 of the sleeve member which engages the surface on which the coaster rests. It is thus possible for the coaster to absorb a considerable amount of moisture before there is any likelihood of damage to the surface on which the coaster rests.

Although the sleeve member 5 is preferably of knit fabric because of the inherent resiliency of such fabric, it is possible to form the sleeve member of woven or other types of fabric. The use of a terry knit fabric on the portions of the sleeve member which are exposed during use of the coaster is preferred because of the decorative and cushioning effect of such fabric, but other decorative schemes may be resorted to, such as the use of patterns in the fabric.

I have illustrated and described what I now consider to be the preferred forms of the invention. It will be understood that variations may be made without departing from the broader scope of the invention which is defined by the following claims.

Having thus described my invention, I claim:

1. A coaster for drinking vessels, comprising a ring-like member of inverted frusto-conical shape, open at its upper and lower ends and arranged to receive the bottom

of a drinking vessel within the larger upper end thereof, and a generally tubular fabric sleeve member of moisture absorbent textile material, an intermediate portion of the length of said sleeve member surrounding and covering the outer surface of said body member, the lower end portion of said sleeve member being constricted to a reduced diameter and at least partially closing the lower end of said body member, the upper end portion of said sleeve member being resiliently constricted to a reduced diameter and extending downwardly into the interior of said body member to form a fabric liner for the upper portion of the interior surface of said body member.

2. A coaster for drinking vessels, comprising a ring-like body member open at its upper and lower ends and arranged to receive the bottom of a drinking vessel therein, and a generally tubular fabric sleeve member of moisture absorbent textile material, the end portions of said sleeve member having resiliently stretchable strands extending therearound and normally constricting such end portions to diameters less than the minimum diameter of said body member, the intermediate portion of the length of said sleeve member surrounding and covering the outer surface of said body member, one end portion of said sleeve member partially closing the lower end of said body member, and the opposite end portion of said sleeve member extending over the upper end of said body member and downwardly into said body member to form a fabric lining for the upper portion of the interior of said body member.

3. A coaster as defined by claim 2 in which at least said intermediate portion of said sleeve member is of terry knit fabric.

4. A coaster for drinking vessels comprising a ring-like body member open at its upper end and arranged to receive the bottom of a drinking vessel therein, and a generally tubular fabric sleeve member of moisture absorbent textile material, an intermediate portion of the length of said sleeve member surrounding and covering the outer surface of said body member, the upper and lower end portions of said sleeve member being of lesser diameter than said intermediate portion thereof, the lower end portion of said sleeve member extending beneath the lower end of said body member to form a fabric base for said coaster, and the upper end portion of said sleeve member extending over the top of said body member and downwardly into the interior of said body member to provide a fabric liner for at least the upper portion of the inner surface of said body member.

5. A coaster as defined by claim 4 in which said ring-like body member is of resiliently stretchable material to enable the coaster to accommodate drinking vessel bottoms of different sizes.

6. A coaster as defined by claim 4 in which said ring-like body member is of inverted frusto-conical shape.

7. A coaster as defined by claim 4 in which at least said intermediate portion of the length of said sleeve member is of terry knit fabric.

8. A coaster as defined by claim 4 in which said sleeve member is of knit fabric and in which said upper and lower end portions thereof have resiliently stretchable yarns extending therearound to permit said upper and lower end portions to be resiliently stretched to increase the diameters thereof.

9. A coaster as defined by claim 4 in which said body member is a split ring.
